(57) **CLAIM**

We claim the ornamental design for a sensor housing for outdoor luminaire, as shown and described.

DESCRIPTION

FIG. 1 is a top perspective view of a sensor housing for outdoor luminaire in accordance with the present design; FIG. 2 is a top view thereof;

FIG. 3 is a front view thereof;

FIG. 4 is a side thereof, the opposite side view being the same;

FIG. 5 is a rear view thereof; and,

FIG. 6 is a bottom view thereof.

In the drawings, the broken lines depict environmental subject matter only and form no part of the claimed design.
